UNITED STATES PATENT OFFICE.

ROSE GAYGEN, OF DETROIT, MICHIGAN.

DESIGN FOR A PEANUT BIRD.

Application filed October 19, 1923. Serial No. 7,554. Term of patent 3½ years.

To all whom it may concern:

Be it known that I, ROSE GAYGEN, a citizen of the United States, residing at Detroit, in the county of Wayne and State of Michigan, have invented a new, original, and ornamental Design for a Peanut Bird, of which the following is a specification, reference being had to the accompanying drawing, forming part thereof.

The figure is a perspective view of a peanut bird, showing my new design.

The peanut bird is made from a peanut mounted on a match stick supported by an inverted U-shaped pipe cleaner, the peanut being decorated by slitted and curled tissue paper representing plumage, and by markings for bird features and feathers.

I claim:—

The ornamental design for a peanut bird, as shown.

ROSE GAYGEN.
